The ornamental design for a set of educational character puppets, as shown and described.

DESCRIPTION

FIG. 1 is a front elevational view of the set of educational character puppets showing my new design;

FIG. 2 is a rear elevational view thereof;

FIG. 3 is an enlarged scale left side elevational view thereof;

FIG. 4 is an enlarged scale right side elevational view thereof;

FIG. 5 is an enlarged scale top plan view thereof;

FIG. 6 is an enlarged scale bottom plan view thereof; and,

FIG. 7 is an enlarged scale front elevational view of a second embodiment of FIG. 1, the only difference residing in the appearance of the circular hat.

FIG. 1

FIG. 2

*FIG. 3**FIG. 4*FIG. 5

FIG. 6

FIG. 7
